INTERNAL COMBUSTION ENGINE

Karl Angel, Montreal, Quebec, Canada

Application September 26, 1932, Serial No. 634,815

3 Claims. (Cl. 123—65)

The invention relates to an internal combustion engine, as described in the present specification and illustrated in the accompanying drawings that form part of the same.

5 The invention consists essentially in distributing and multiplying the inlet valves and proportionately reducing their dimensions for automatic operation in respect to the fuel charge and accompanying ingress of air as pointed out in the claims 10 for novelty following a description in detail of the preferred constructional features.

The objects of the invention are to achieve through-scavenging without the necessity of mechanically operating poppet-valves, piston 15 valves, or opposed pistons; to determine the degree of super-charging or pressure-charging by the scavenging pressure, through the closing of the exhaust ports by the piston mechanically connected to the crank shaft in the conventional 20 manner and therefore definitely timed; to prevent the closure of the inlet valves until the pressure in the cylinder has risen to equal that of the scavenging pressure; to attain the desired time-area necessary for scavenging and charging; to 25 use valves of relatively small dimensions and to so decrease their weight as to permit of high rotational engine speeds being attained without building up high inertia forces in the valves; to prevent the overheating of the valves by proper cooling; to standardize the valve sizes as much as 30 possible so that they can be used in a varying number of cylinder bores and therefore facilitate the low cost of their production; and generally to provide a reliable combustion engine simple in 35 operation and efficient for the purposes set forth.

Like numerals of reference indicate corresponding parts in the various figures.

Referring to the drawings, Figure 1 is a fragmentary elevational sectional view of an internal combustion engine.

Figure 2 is a fragmentary cross sectional view on the lines 2—2 in Figure 1.

Figure 3 is a diagrammatic fragmentary elevational sectional view showing the inlet valves applied to an internal combustion engine having a conical head.

Figures 4 and 5 are diagrammatic plan views showing different possible ways of mounting the valve housings at different angles.

50 Figure 6 is a diagrammatic cross sectional view through the head of an internal combustion engine illustrating a possible way of grouping the valve housings in circles of different diameter.

55 Figure 7 is an enlarged fragmentary sectional view of a modified form of valve.

Figure 8 is a vertical diagrammatic sectional view showing the invention applied to a double acting internal combustion engine.

Referring to the drawings, the numeral 10 indicates a two stroke engine having the cylinder 11, the piston 12 and the detachable cylinder head 13.

The cylinder head 13 has an injection valve or spark plug opening 14 and the tubular scavenging valve housings 15 completely surrounded by 10 cooling water contained in the chamber 16.

Each valve housing 15 has a valve seat 17 located at its lower end, the valve guide 18 for the non-return valve 19 maintained on its seat 17 by the spring 20 and the adjustable stop 21 limiting the lift of said valve 19.

The cylinder head 13 has the annular cover or inlet manifold 22 forming a chamber 23 into which the air or gas is introduced under pressure from a generator through the port 24.

20 The chamber 23 has the threaded opening 25 adapted to be engaged by a safety valve. The annular cover is sealed against leakage by the gaskets 26 and 27 and has the central well opening 28 communicating with the injector or spark 25 plug opening 14.

The cylinder 11 has a belt of exhaust ports 29 located at the lower end of the stroke of the piston 12 and is surrounded by a water jacket 30 communicating through the tube 31 with the 30 chamber 16 of the cylinder head 13.

It will be observed in the drawings that the scavenging or inlet valves 19 are in an open position and the dotted lines and arrows indicate the parallel paths of the scavenging air or 35 gas streams downwards towards the exhaust ports.

In the operation of this invention, at the end of the firing stroke, the piston uncovers the exhaust ports through which the products of combustion escape outbalancing the pressure of the gases contained in the chamber 23 of the annular inlet manifold 22. The difference in pressures, thus created force the non-return valves 19 to open allowing the fresh air or gas mixture to rush 45 in parallel paths uniformly pushing out the balance of the products of combustion thereby allowing only fresh mixture to remain, for as can easily be understood the piston continues to travel and is now travelling upwards on the compression 50 stroke, closing the exhaust ports just as the fresh mixture is about to escape.

Meanwhile, the fresh mixture continues to rush in against the column of gases already in the cylinder until the pressures in the chamber 16 55

and combustion chamber 32 are equalized when the inlet valves close under the pressure of the springs 20.

The pushing up of the column of gases by the piston against the incoming air or mixture creates a turbulence which stirs the mixture which once the piston valves are closed, is compressed and ready for the next firing stroke when another cycle starts.

10 10 The tension of the springs 20 can be regulated by the nuts 33; as can easily be understood, a number of valves can thus be made to open or close in advance of the others thereby assuring a flow of air or gas mixture proportionally varying in volume with the pressure in the cylinder 11.

15 Figure 3 illustrates that the valve housings are not limited to cylinders having flat heads, but can be applied with equal facility to conical heads or any other shaped head, that may occur in an internal combustion engine.

20 20 The valve housings may be parallel to the cylinder or may be radially inclined as shown in Figures 3 and 4 in which the numerals 34 and 35 respectively indicate the parallel housings and the radially inclined housings.

25 30 In order to produce rotational motion of the scavenging or charging medium the valve housings may be either inclined tangentially or both radially and tangentially as shown in Figure 5 in which the numerals 36 and 37 respectively indicate the tangentially inclined housings and the radially and tangentially inclined housings.

35 Figure 6 illustrates that the valve housings may be arranged in circles of different diameter, or staggered in order to increase the number of valves or to permit of the best location of spark plugs, injection nozzles and safety valves.

40 45 Figure 7 illustrates that the valve stems may be relatively short and not necessarily extend through the cylinder head, thus decreasing the weight of the valves which may be further lightened by boring out the valve stems as indicated at 38.

50 45 Figure 8 indicates a method of applying the invention to a double-acting two-stroke engine. In this modified form the cylinder is indicated by the numeral 39 and has the central belt of exhaust ports 40 cooperating with both combustion chambers 41 and 42.

55 Only a few of the modifications have been illustrated or described. It is evident that a greater number could be made without departing from the spirit of the invention.

What I claim is:—

1. In an internal combustion engine, a cylinder forming a combustion chamber having a fuel inlet and exhaust ports, a valve block forming a head for said cylinder, and a pressure air chamber capping said head, a safety valve to said air chamber and communicating with said cylinder through said valve block and automatically scavenging said combustion chamber, valves in the communication passages resiliently suspended 10 and susceptible to said air pressure, and a piston operating in said combustion chamber and adapted to expose the exhaust ports for scavenging, thereby relieving the pressure from under the valves to allow passage of the air under pressure from the air chamber to the combustion chamber.

2. In an internal combustion engine, a cylinder forming a combustion chamber having a fuel inlet and exhaust ports, a valve block forming a head for said cylinder, and a pressure air chamber capping said head, a safety valve to said air chamber and communicating through passages in annular rows surrounding the fuel inlet with said cylinder through said valve block and automatically scavenging said combustion chamber, valves in the communication passages resiliently suspended and susceptible to said air pressure, and a piston operating in said combustion chamber and adapted to expose the exhaust ports for scavenging, thereby relieving the pressure from under the valves to allow passage of the air under pressure from the air chamber to the combustion chamber.

3. In an internal combustion engine, a cylinder forming a combustion chamber having a fuel inlet and exhaust ports, a valve block forming a head for said cylinder, and a pressure air chamber capping said head, a safety valve to said air chamber and communicating through passages in annular rows surrounding the fuel inlet with said cylinder said passages being inclined circumferentially through said valve block and automatically scavenging said combustion chamber, valves in the communication passages resiliently suspended and susceptible to said air pressure, and a piston operating in said combustion chamber and adapted to expose the exhaust ports for scavenging, thereby relieving the pressure from under the valves to allow passage of the air under pressure from the air chamber to the combustion chamber.

KARL ANGEL.
